UNITED STATES PATENT OFFICE.

PRESTON M. SMITH, OF EAST ORANGE, AND EDWARD M. SQUAREY, OF SOUTH ORANGE, NEW JERSEY, ASSIGNORS TO U. S. TOOL COMPANY, INC., A CORPORATION OF NEW JERSEY.

ROTOR SYSTEM FOR CONDENSERS.

Application filed April 28, 1924. Serial No. 709,394.

To all whom it may concern:

Be it known that we, PRESTON M. SMITH, a citizen of the United States, and EDWARD M. SQUAREY, a citizen of the Commonwealth 5 of Newfoundland, and residents, respectively, of East Orange and South Orange, county of Essex, and State of New Jersey, have invented a new and useful Improvement in Rotor Systems for Condensers, of 10 which the following is a specification.

In the construction and use of the modern variable condenser as an accessory in radio-telephony, many difficulties have arisen in the way of capacity losses of such a nature 15 as often to render an otherwise valuable instrument useless. These losses, when handling the very weak electric currents to which the instrument is adapted, are hard to trace to their exact source, and when found, 20 the conditions are such as to be almost incapable of remedy without great expense and much trouble. After many tests, we find that many of the losses are traceable, not so much to the material of which the 25 instrument is constructed as to imperfect contact of metal to metal in the plate connections. We have, therefore, designed an improved form of rotor, wherein the several plates forming it are integrally connected, 30 so as to comprise a single integral metallic strip from one end of the plate system to the other, thereby making the conductor homogeneous throughout.

The object of our invention, therefore, is 35 to provide a rotor for a variable condenser with a plate system which is continuous, whereby the capacity losses therein may be reduced to a minimum, and that minimum so infinitesimal as to be incapable of measurement.

In the accompanying drawing forming a part hereof, we have shown an embodiment 40 of our improvement, wherein

Fig. 1 is a plan of a strip of sheet metal, 45 showing the layout of a series of connected rotor plates.

Fig. 2 is a rear edge view of a set of the plates in their folded form.

Fig. 3 is a front edge view of the same.

Fig. 4 is a side view of an assembled rotor.

Similar reference numerals refer to like parts throughout the specification and drawing.

The strip of sheet metal 1 is selected of a 50 width sufficient to stamp the rotor plates

therefrom, but of only one-half the usual thickness or gage of such plates. The plates 2 are cut or punched from the strip of metal in the usual semi-circular form, but with the connecting tangs 3 between the arcuate edges 60 thereof, and the tangs 4 connecting the hubs of the plates. These hubs 5 are also of the usual shape, and consist of smaller semicircular projections from the straight edges of the plates, and have the apertures 6 there- 65 through, by which the plates are assembled upon the rotor shaft 7, upon which they are clamped between the usual collar 8 and the nut 9. When a complete set of the plates is stamped from the metal strip, they are folded across the tangs 3 along the dotted lines, and doubly folded across the tangs 4, into the form shown in Figs. 2 and 3. The tangs 3 are short, and when folded, the backs 70 of the plates which they connect are brought back to back in continuous contact throughout. The tangs 4 are of a length sufficient, when folded or bent as shown, to afford 75 the requisite space between the plates to permit the proper interleaving with the plates 80 of the condenser stator (not shown).

The series of plates thus connected together are then assembled upon the shaft 7, with the spacing washers 10 between adjacent plates, and clamped as above described. 85 between the fixed collar 8 and the clamping nut 9. It is then ready for assembly in the complete condenser.

If desired, the end plate of the series may be provided with a long tang 11, which is 90 bent around and over the collar 8, and extends along a groove in the side of the shaft 7, to a point outside of the condenser frame (not shown) for connection with the usual "pig-tail" to the outside circuit, the purpose 95 being to afford a continuous homogeneous metal connection between the entire rotor plate system and the external circuit.

The rotor system thus described is designed especially for use in connection with 100 the stator plate system described in the application of Edward M. Squarey, Frederick Koch and Alwyn E. Borton, Serial No. 709,395 filed of even date herewith, and to which reference is made.

The making of the rotor plate system from sheet metal of but half that usually employed enables us to preserve the usual thickness of the individual plates, since when the connected plates are folded as described, 110

the resulting duplex plates are only of such usual thickness. The metal being continuous from one end of the plate system to the other, completely obviates the capacity losses which are invariably found to be present in condensers wherein the plates are clamped together in mere metallic contact. In other words, we provide a continuous homogeneous metallic plate system.

10 We claim:—

1. A rotor plate system for variable plate condensers comprising a plurality of plate members, arranged in parallel spaced relation, each plate member being composed of two plates integrally connected upon their arcuate edges and folded thereat back to back in continuous contact, and each connected by an integral tang to the next adjacent plate member.
- 15 2. A rotor plate system for variable condensers, comprising a plurality of sheet metal plates of semicircular shape arranged in pairs, each pair being connected together by an integral tang at their arcuate edges

and folded thereat back to back to form a single duplex plate member, each of said plates being connected to the adjacent plate of the next adjoining plate member by an integral tang, whereby a plurality of plate members spaced apart and integrally connected is formed.

3. A rotor plate system for variable condensers, comprising a plurality of semicircular plates stamped from a single strip of sheet metal and arranged in pairs having their arcuate edges adjacent to each other, and integrally connected by short tangs, the straight edge of each plate being connected by an integral tang to the straight edge of the adjacent plate of the next adjoining pair of plates, whereby when said pairs of plates are folded back to back across said first named tangs and doubly folded across said second-named tangs, a plurality of duplex plate members arranged in parallel spaced relation is formed.

PRESTON M. SMITH.
EDWARD M. SQUAREY.
